UNITED STATES PATENT OFFICE.

CHARLES WILLIAM SMITH, OF PHILADELPHIA, PENNSYLVANIA, ASSIGNOR TO KEYSTONE TYPE FOUNDRY, OF PHILADELPHIA, PENNSYLVANIA.

DESIGN FOR A FONT OF TYPE.

SPECIFICATION forming part of Design No. 37,379, dated March 21, 1905.

Application filed November 15, 1904. Serial No. 232,900. Term of patent 7 years.

To all whom it may concern:

Be it known that I, CHARLES WILLIAM SMITH, a citizen of the United States, residing at Philadelphia, in the county of Philadelphia and State of Pennsylvania, have invented a certain new, original, and ornamental Design for a Font of Type, of which the following is a specification.

Said original design for a font of type is clearly illustrated in the accompanying drawing, wherein the distinguishing characteristics will be plainly seen, said drawing being a typographical impression of a font of type of the said ornamental design.

What I claim as new, and desire to secure 15 by Letters Patent, is—

The ornamental design for a font of printing-type as shown in the accompanying drawing.
